UNITED STATES PATENT OFFICE.

CHARLES H. WILD, OF BALTIMORE, MARYLAND, ASSIGNOR TO BURT MACHINE COMPANY, INCORPORATED, A CORPORATION OF MARYLAND.

CAN-LABELING MACHINE.

Application filed August 26, 1924. Serial No. 734,160.

In the operation of can labeling machines where various commodities are packed and cans of several different sizes are used, frequent adjustments are necessary as to the 5 spacing of the can feeding belt from the ways on account of the variation in the diameter of the cans and corresponding adjustments of the lap pasting mechanism are also necessary on account of the variation in the length 10 of the labels and adjustment of the position of the cement or glue pot is necessary on account of the variation in the circumference of the cans.

In further explanation it may be said that 15 the labels being picked up by a spot of glue on the outside of each can, the distance from the point at which the cans are spotted to the label table must be varied to suit the circumference of the cans being treated in 20 order that the spot of glue or cement on each can may contact the label at a point near the end and pick the label up in due course; and on account of the variation in length of the 25 labels consequent to the variation in circumference of the cans, the position of the label pasting mechanism relatively to the centre of the label table must be changed as the size of the cans and adjustment of the feed belt are changed in order that the lap pasting 30 mechanism may contact the labels at the lap ends.

As the adjustment of the belt involves the adjustment of the uprights supporting the respective belt pulleys at both ends of the 35 machine, there are at least four adjustments to be made each time there is a change from the labeling of cans of one diameter to the labeling of cans of a different diameter.

One of the objects of the present invention 40 is to assemble or connect the various adjustments under and to a single control, so that the desired changes may be made by means of a single crank or hand-wheel, or by any suitable control. My invention, however, contemplates the grouping of these 45 adjustments in various combinations as may be desired.

My invention further relates to a label feed 50 particularly adapted to can labeling machines. Machines of this general type have been previously constructed with a label feed operated by the cans. In this type of machine the label feeding device includes a finger which projects into the path of the 55 cans and is moved by the cans as they pass,

the label feed being in this way controlled by the cans, and actuated thereby either directly or indirectly. The present device is more logical in its arrangement and exact in its operation in that it is directly controlled by the height of the pack of labels.

In accordance with the present practice, the lap ends of the labels are placed in condition to closely engage the cans by means of a curler bar which extends transversely of 65 the machine and engages each label on what may be termed the inside surface adjacent the lap end. The curler bar is mounted to move up and down, and it rests on the top label. The labels are taken up by the cans 70 one at a time from the pack and the ends are pulled from beneath the curler, giving them a bend or curl corresponding to the curvature of the outer surfaces of the corresponding cans, so that they tend to lie closely 75 against the sides of the cans when finally secured in position. The position of the curler necessarily corresponds to the position of the top label in the pack, the labels being compressed to a considerable extent, and the 80 label feed or label table feed is connected to and controlled by the position of the label curler. In this way the operation of the device is improved and made more directly 85 responsive to the element controlled, i. e., the position of the top label in the pack.

The label feed also comprises a pawl which is oscillated continuously by means of a rotary member actuated from and by the machine drive, the operation of the pawl being effective or ineffective to move the labels in accordance with the position of the label 90 curler.

The invention also relates to the design and construction of the label curling bar, 95 giving it several alternative label-engaging surfaces and wearing surfaces. Also the curler surface is slotted or grooved transversely, preventing complete removal of the paste from the label by the bar.

The cans are spotted with cement or paste by means of rollers over which the cans pass on the ways, which rollers dip in the pot of cement or glue which is maintained in a liquid condition by heating. One feature of 105 the invention relates to the control of the level of the liquid cement in the pot, at the same time maintaining a reserve supply of material. This is accomplished by means of 110 a reservoir at one side of the machine hav-

ing a comparatively large area in a horizontal plane, forming a receptacle in which the hard cement may be placed. As it is undesirable to have the shaft submerged, 5 this receptacle has its top edges on a level with or below the paste roller shaft, preventing the application of an excess of glue to the cans. The cement is normally solid or semi-solid and becomes liquid when heated 10 and if an excess is placed in the reservoir, it will overflow at this point instead of causing the liquid to rise above the level of the shaft of the glue-spotting rolls. The reservoir is connected with the glue pot by 15 a narrow slot which prevents passage to the rolls of any of the particles of solid unmelted glue or cement.

It not infrequently happens that the labels 20 as furnished are as a whole irregularly cut or irregularly printed, the printing not being in line with the edges of the labels. To bring the print into the desired position in relation to the edges of the cans, an adjustment of the label guides relatively to the 25 ways is desirable. In the present instance I have provided an adjustment of each guide relatively to the other, also providing for adjustment by the same mechanism of both guides laterally at either or both ends so 30 that when the desired spacing has been attained, the angle of the guides may be changed to suit the printing without changing their relation to each other.

In the accompanying drawings I have 35 illustrated the various parts and features of a can labeling machine embodying my invention in the preferred form.

In the drawings—

Figure 1 is a side elevation of the delivery end of the machine.

Figure 2 is an elevation taken from the same side, showing the receiving or feed end of the machine.

Figure 3 is a top plan view of the delivery end of the machine.

Figure 4 is a plan view of the feeding or receiving end of the machine.

Figure 5 is a side elevation taken from the side of the machine adjacent the observer in all of the above-mentioned figures, i. e., the left side of the machine looking at the same in the direction of the feed, showing the label feeding mechanism.

Figure 6 is an elevation of the label feeding mechanism taken from the right of the same as seen in Figure 5.

Figure 7 is a section on the line 7, 7 of Figure 6.

Figure 8 is a section through the glue pot on line 8, 8, Figure 9.

Figure 9 is a plan of the glue pot reservoir, etc.

Figure 10 is a section of the same on the line 10, 10 of Figure 9.

Figure 11 is an elevation of the curler

bar in accordance with the preferred form of my invention.

Figure 12 is a section through the same on the line 12, 12 of Figure 11.

Figure 13 is an elevation of another form 70 of label curler in accordance with my invention.

Figure 14 is a section through the same on the line 14, 14 of Figure 13.

Figure 15 is an elevation of still another 75 form of curler in accordance with my invention; and

Figure 16 is a section through the same on the line 16, 16 of Figure 15.

Figure 17 is a transverse section on the 80 line 17, 17, Figure 1.

Figure 18 is a plan of the label table and surrounding parts, reading from the side of the machine opposite to that from which Figures 3 and 4 are taken.

Figure 19 is a section on the line 19, 19 of Figure 18.

Figure 20 is an elevation, looking at the same portion of the machine as shown in Figure 19 from the front.

Figure 21 is an elevation of the curler bar mechanism and a portion of the label table, looking from the side remote from the observer in Figure 18.

Figure 22 is a section on the line 22, 22, 95 Fig. 21, looking in the direction of the arrow in that figure.

Figure 23 is an elevation showing the belt presser, the same being taken from the same point as Figure 21.

Fig. 23' is a section on line 23', 23', Fig. 23.

Figure 24 is an enlarged view in the nature of a section on the line 24, 24, Figure 18, showing the manner of supporting the 105 end of a label guide on the adjusting screws.

Referring to the drawings by numerals, each of which designates the same or similar parts in the different figures; the machine as shown includes two parallel longitudinal 110 side frame members, or beams 1 and 2 extending practically from one end of the machine to the other and supported on a suitable pedestal or leg structure 3. The various operative elements of the machine are 115 mounted on the beams 1 and 2.

In the labeling operation the cans are passed through the machine from right to left of the machine, as seen in Figures 1 to 4. As the operator stands on the side of the machine remote from the observer in these figures, and therefore faces in a direction opposite to that of the observer in these figures, the direction of traverse of the cans might properly be referred to as from left to right. However, the description of this operation, so far as such description is necessary, will relate to the machine as seen in the drawings, in which view of the machine the cans pass from right to left.

In passing through the machine the cans roll along the ways between frames 1 and 2, the cans being propelled or rolled by frictional contact with the bottom surface or 5 traverse 5 of the can feed belts 6. The belts 6, shown in plan in Figures 3 and 4, are supported upon and run over pulleys 7 and 8 at the opposite ends of the machine, the pulleys being supported upon brackets 9 and 10 secured to the beams 1 and 2. As 10 shown, each of the brackets 9 and 10 has a base portion 12 enclosing the correspond- 15 ing beam 1, 2, the bracket being preferably secured to the beam by means of a set screw 13, so that the brackets may be adjusted from time to time to take up the slack of the belt or for other purposes.

In the form of the machine shown and in accordance with the preferred form of the 20 invention, each of the brackets 9 and 10 is provided with a vertical guide 14 which carries an upright 15 mounted to slide vertically in said bearing. The upright 15 carries at its upper end a suitable bearing 25 member 16 for the pulley shafts 17 and 17', and the lower portion of the uprights 15 is provided for five or six inches of its length or more in proportion to the extent of the 30 adjustability desired with rack teeth 18 en- gaged by a pinion 19 on a transverse shaft 20 or 20' at the respective ends of this machine, shown as cut in the shaft which is supported in a suitable bearing in a depend- 35 ing arm 21 of the brackets 9 and 10, respec- tively.

The shaft 17 is driven from any suitable source of power, as electric motor 170', which carries bevelled gearing not shown, mounted in casing 171' on the motor frame, 40 which gearing drives immediately the short shaft 172' mounted in the casing 171' and connected by universal joint 173' to the square outer member 174' of telescoping shaft 175', which with the universal joints 45 compensates the various adjustments of the shaft 17 and the pulley 7. The outer mem- 50 ber 174' carries an inner member in the form of a square rod 176', which fits the outer member 174' and slides longitudinally relatively thereto, and turns therewith. This inner member 176' is connected by universal joint 177' with a short shaft 178' mounted in a bevelled gear casing 179' on the shaft 17, the shaft 178' having mounted on its 55 inner end a bevel pinion 180' shown as a spiral pinion, and meshing with a correspond- ing bevel gear 181' secured to the shaft 17.

To reduce the multiplicity of adjustments 60 incident to treating cans of different diam- eters and particularly to changing the ma- chine from the adjustment appropriate to one diameter of cans to the adjustment ap- 65 propriate to the treatment of cans of a dif- ferent diameter, I have connected the shafts

20, 20' at each end of the machine by suit- able gearing, so that by rotation of one of the shafts 20, 20' which causes the pinion 10 on said shaft to engage the rack teeth 18 moving the rack and pulley shaft and pul- 70 leys carried thereby up or down to adjust the position of the belt, the corresponding shaft 20, 20' at the other end of the ma- chine will be rotated, imparting a similar and equal motion to the shaft 17' and belt 75 pulleys and belt at the opposite end of the machine.

In the form of the invention illustrated a toothed sprocket 23, 23' is mounted on and rigidly secured to each of the pinion shafts 80 20, 20' at the opposite ends of the machine, and the sprocket at each end is engaged by a suitable chain or sprocket chain 24. As the rotation of the shafts 20, 20' providing 85 for the adjustment of the belt consists in but a few turns at the most, first in one di- rection and then the other direction as the belt is moved up and down, and the span from one shaft 20 to the other is of consid- 90 erable extent, as shown, a short piece of chain 24 at each end of the machine extends around the toothed sprocket and beyond the point of engagement with the same for a few inches at each end of the chain, the corresponding ends of the chain being con- 95 nected by crossed tension rods 25 and 26 which give the effect of a crossed belt or chain, so that when one shaft is rotated either in a righthanded or lefthanded di- 100 rection, the corresponding shaft at the other end of the machine is rotated through a similar arc in the opposite direction, one right-handed and the other left-handed. The insertion of the cross rods 25 to 26 in the chain not only reduces the expense in- 105 cident to providing a chain which would extend the entire length of the machine, but reduces the back lash incident to a similar unsupported length of flexible chain, caus- 110 ing the driven shaft to respond immediate- ly to the rotation of the driving shaft, maintaining a constant relation between the respective adjustments of the belt and belt pulleys at the opposite ends of the ma- chine, so that when the chain is properly 115 connected, the adjustment of the belts and pulleys at the feed end of the machine is almost exactly equal and similar to the cor- 120 responding adjustment of the belts and pul- leys at the delivery end of the machine.

It will be easily understood, as previous- 125 ly outlined, that the position of the cement spotting rollers by which cement is placed on the cans for the purpose of picking up the labels and the position of the paste ap- 130 plying belt which coats the lap ends of the labels, should be changed to correspond to and with each adjustment of the belt, in other words, to correspond to the diameter of the cans being handled.

In accordance with the present invention the machine is so devised and arranged as to perform the adjustment of the can spotting rolls and the lap pasting belt simultaneously and conjointly with the adjustment of the feed belt. To this end the paste pot 28 and lap pasting belt 29 are mounted to slide longitudinally of the machine on sliding carriers 30 and 31 which engage the side frame members 1 and 2, respectively.

The carrier members 31 enclose the side frames 1 and the carrier members 30 are provided with washers 32 secured to the carrier members by bolts 33, the washers being extended over the top edges of the side frame members 1 and 2. The carriage 34 for the paste pot and belt, including the carrier members 30 and 31, is in effect integral. It consists, as shown, of longitudinal horizontal arms 35 at each side, see Figure 3, the carrier 30 being formed integral with said horizontal arm at one end and the arm being provided with a boss 36 at the other end, which boss is fastened to the carrier member 31 by means of a bolt 37. The lap pasting belt 29 is driven by pulley 38 mounted to slide on a horizontal shaft 39 to which it is keyed, the key slot being shown at 40 in Figure 1.

In the form of the invention shown the pulley 39 is provided with a hub grooved at 41, and this groove is engaged by a hook 42, see Figure 3, secured to the upright 44 on the carrier 31 by means of a screw 45 engaging the slot 46. The shaft 39 is driven in rotation by means of a bevelled gear 55 secured to the shaft and a corresponding bevelled gear 56 intermeshing therewith and carried on a stud 57 at right angles to the shaft, said bevelled gear being rigidly connected to a pulley 58 which is driven by a belt 59 which is in turn driven by a pulley 60 on the shaft 17' at the feed end of the machine, see Figure 4. The carriage 34 also carries the pad 51 and way 52, suitably mounted to slide on frames 1, 2.

To perform the automatic adjustment referred to, the carriage 34 is provided with a rack 47 which extends in the direction of the feed, i. e., longitudinally of the machine. This rack is engaged by a toothed gear 48 on the shaft 20 at the delivery end of the machine, i. e., at the left in Figure 1. The shaft 20 is provided with a hand-wheel 50 shown in plan in Figure 3, and it is apparent that on rotation of the shaft 20 by means of the hand-wheel or otherwise, not only will the feed belt be moved up and down to provide for the engagement of cans of different diameters, but the lap pasting belt carriage with the paste pot and pulley will be moved longitudinally of the machine in a ratio and direction which can be made to correspond to the adjustment of the feed belt.

In order to vary the adjustment of these parts, the rack 47 may be adjusted relatively to the carriage 34. It is hollowed out longitudinally and threaded to receive or otherwise provided with a longitudinal feed screw 80 having a hand wheel 81 at one end and having a swivel for engagement with bracket 82 depending from the carriage 34 at the other end. By rotation of the screw 80, the carriage 34 with the lap pasting mechanism is moved relatively to the rack 47.

In adapting the machine for use in labeling cans of different diameters, it is, as already pointed out, necessary to move the cement spotting appliance or glue pot as distinguished from the lap pasting mechanism, along the ways, i. e., in the direction of the feed as the circumference of the cans being treated varies. As the distance of the cement or glue spotting device from the ends of the labels which are picked up by the cans must obviously correspond to the circumference of the cans.

To this end the glue or cement pot 65 which is mounted on a suitable support 66 to slide on the longitudinal beams 1, is provided with a longitudinally extending rack 67, which, as shown, is adjustably connected to the glue pot at one end at 68' and extends to the right of the machine, as seen in Figure 2, projecting beyond the beams in the direction of the intake or receiving end of the machine. The rack 67 is engaged by a toothed gear 68 mounted on a shaft 20' at the feed end of the machine, which, as already pointed out, is driven from the chain 24, 25, 26 from the gear 23 on the shaft 20 at the delivery end of the machine. It is obvious, in view of the construction described, that on rotation of the hand-wheel 50 or otherwise on adjustment of the position of the feed belt by rotation of the pinions 19 on the shafts 20, 20', that the cement pot 65 will be correspondingly adjusted in the direction of the feed toward and from the label table, the paste pot moving away from the label table as the feed belt moves upwardly, i. e., the larger the diameter of the cans being treated, the greater the distance of the paste pot from the label table.

In order to provide for the adjustment of the glue spotting mechanism relatively to the rack 67 so as to permit change of relation between the belt position and that of the glue spotting mechanism, I have provided a screw 67' parallel to the rack 67 and preferably placed in bore in the rack. This screw 67' is turned by a hand-wheel 68' on the end of the screw and the screw 67' in turn engages a thread 69' formed in the rack, and there is a swivel connection 68' between the screw and the cement pot, providing for adjustment or change of adjustment of the glue pot relatively to the belt.

The paste spotting rollers 69 which are of

the usual type are driven by a belt 70 engaging a pulley 71 fixed on the shaft 71' connected by gearing 188 to shaft 72 which carries the rollers 69 in pot 65, all said members 5 being mounted on and moved with the cement pot. This belt 70 is in turn driven by and from a pulley 73 on the shaft 17' which carries the belt pulleys 8 at the feed end of the machine, and in order to take up the 10 slack, i. e., to maintain the tension of the belt in the various positions of the apparatus, the belt is in turn engaged by idler pulleys or rollers 74, one engaging each lap of the belt, both pulleys being on the same 15 side of the respective laps of the belt, which pulleys or rollers are carried by a swinging arm 75, which swings about a stud 76 on the bearing member 16, the arm being in turn actuated by a coil spring 78 coiled 20 about the stud and engaging at one end the hub of the arm and at the other end the bearing 16 pressing the rollers against the belt.

Referring now to Figures 5 and 6, I have 25 illustrated in these figures an improved form of label feed, which is automatically power operated from the drive of the machine and controlled not by the cans but by the height of the label pack. In the present instance 30 the label curler is utilized for this purpose, i. e., as a means for controlling the label feed in response to the variation of the height of the pack of labels.

The label table 85, Figure 1, is supported 35 on and fed up and down by means of an upright 86 having rack teeth 87 on the lower portion and mounted to slide vertically in bearing 87' on the machine frame. This rack is engaged by pinion 88 on a transverse 40 horizontal shaft 89 which also carries fixed thereon a ratchet wheel 90 engaged by pawls 91 and 92. The former of these is a locking pawl pivoted on a pin 93 in the frame of the machine and held normally in 45 engagement by a spring 94, wound about pin 94' seated in the frame and adjusted about the pin by collar 94'' thereon held by set-screw 94'''. The other pawl 92 is an oscillating or feeding pawl mounted on the 50 arm 95 to swing about a pin 96 in said arm and having a tendency to engage the ratchet imparted to it by the spring 97 mounted on collar 98, on pin 99 seated in the lever arm 95, the arrangement being similar to that of 55 spring 94.

The arm 95 is pivoted to swing about shaft 89 and is actuated by an eccentric pin and roller 100, carried on shaft 102 of pulley 101 which is driven by belt 104. The arm 95 60 is held down against the roller by gravity and by the spring 103, the stroke of the pawl being sufficient to move the ratchet one tooth for each oscillation when the pawl is in operative position. Both pawls are given 65 a tendency to remain in constant engage-

ment with the ratchet by virtue of the springs 94, 97, but they are both controlled by a shield or pawl arm 105 secured to shaft 106, parallel to shaft 102. The pawl 91 is normally in engagement, being thrown out 70 only when the shield is moved to extreme position by hand, but the pawl 92 is normally held out of engagement with the ratchet 90 by the shield 105. The shaft 106 also carries a bifurcated arm 107 depending 75 from the shaft and fixedly secured thereto as by set-screw 108. The shield 105 extends upwardly, i. e., it is on the opposite side of the shaft, and is provided at its extreme upper end with a hook or offset 109 which 80 engages the tail 110 of the pawl 91 when the shield is operated by hand and swung to the right in Figure 5 for this purpose. Under these circumstances the shield also 85 releases the pawl 92, the release of both pawls in this way permitting the label table to be lowered for the reception of a new charge of labels. The shield 105, however, controls the pawl 92 at all times, the offset 90 or tail 111 of the pawl being in continuous engagement with the pawl bearing surface 112 on the shield, and controlled by way of 95 said shield to operate and feed the label table upward in response to the dropping of the curler bar, which in turn controls the position of the shield through and by way of the following mechanism:

Shield 105 is rigidly secured to the shaft 106 which carries the arm 107 also secured thereto and having spaced lugs 113 which 100 are apertured and threaded to receive aligned oppositely disposed set-screws 114 between which is a depending arm 115 also mounted on shaft 106 and secured in position of adjustment thereon by means of set-screw 116, said arm 115 being definitely positioned relatively to the arm 115 by the set-screws 114 for purposes of adjustment, and then further secured to the shaft by the set-screw 116, so that the shield 105 and the 105 lever arm 115 are in effect both rigidly secured to the shaft 106 and to each other, the parts described merely providing relative adjustment. The position of the shaft 106 and of the pawl shield 105 is determined 110 by the position of the curler bar through the arm 115, which latter, see Figures 5 and 6, engages by means of a slot 117 a radial arm 118 on the shaft 119, the hub 120 of the arm 118 being enclosed between ears 121 115 120 adjustably mounted by means of a pin 122 on the end of a depending bracket 123 on the frame of the machine. The ears are also apertured to pass the shaft 119 which is guided and supported thereby. The shaft 119, as shown, is provided with a keyway 125 124 which engages a suitable key in the hub 120, connecting the hub to the shaft for rotation therewith and providing for a sliding motion of the shaft relatively to the hub 130.

120 held by ears 121 on the bracket 123. The shaft 119, as shown, see Figures 1, 5, 6, 21 and 22, is provided with two hinged joints, 125 near the lower end and 126, near the upper end and the shaft 119 is provided with a radially extending arm 127 having a hub 128 on the shaft, pinned or otherwise secured thereto and enclosed between ears 129 mounted on the end of a bracket 130 10 on the frame to which the ears are connected by a pin 131 passing through the end of the bracket substantially at right angles to the shaft 119, both the pins 131 and the pins 122 permitting the ears to conform to 15 the direction of the shaft 119.

Referring now to Figure 18, which is a plan, the position of the observer being on the opposite side of the machine to that occupied by the observer in Figures 1 and 3, 20 and the like, and also referring to Figures 21 and 22, the label curler 133, to be more specifically described as to its details, is mounted between the ends of swinging arms 134 which rotate or oscillate upon the curler 25 bar shaft 135 which extends across the machine just in front of the label pack, being mounted at each end in brackets 137, one on each side of the machine secured to the base portions of the carriers 31 which carry the 30 paste rolls 38, the pad 51 and the way 52. The swinging arm 134 on the side of the machine nearest the observer in Figure 1, and remote from the observer in Figure 18, is provided with a depending arm 138 integral 35 therewith, see Figure 21, so that the entire member may be referred to as a bell crank lever 139 swinging about the shaft 135 as a centre. The depending arm of the bell crank lever is, as shown, slotted at 140, the 40 slot extending in the direction of a radius from the shaft 135. The arm 127 secured to the upper end of the shaft 119, extending outwardly radially thereof, as already described, is passed through the slot 140, so 45 that all oscillations of the shaft 135 about its centre, are communicated to the shaft 119, substantially at right angles thereto, producing corresponding oscillations of the shaft 119, and in the form of the invention shown 50 the reverse is also true, so that the spring 97 pressing against the pawl 92, serves in the proper adjustment of the parts, to transmit a slight tension to the curler bar, tending to keep it in contact with the labels. 55 In the operation of the machine the label curler rests on the top label of the pack, and moves up and down swinging about the shaft 135 to a slight degree in conformance with the height of the label pack, moving 60 downwardly as the labels are removed. The pawl 92 is shown in engagement with the toothed periphery 90 of the ratchet, but this is the feeding and not the normal position of the pawl. The pawl is normally held out 65 of contact with the teeth by the operation of

the shield 105, as controlled from the label pack by the curler 133, the bell crank 139, arm 127, shaft 119, arm 118, arm 115, bifurcated arm 107 and shaft 106 which carries the shield 105, which in turn is constantly 70 engaged by the tail 111, more properly described as a shoulder of the pawl 92, the latter being pressed down by the spring 97, which in the proper adjustment of the parts applies tension to the entire mechanism. 75 The pawl 92 is oscillated continuously about the centre of the ratchet by the action of the eccentric roller 100 upon the lever arm 95 which swings about the shaft 89 at the centre of the ratchet. 80

As the labels are removed, being taken up one at a time successively by the cans as they pass through the machine, the level of the top of the label pack is lowered to a degree corresponding to the thickness and clearance 85 of the labels, and the curler swings downward correspondingly, and the shield 105 which is controlled from the label curler through the train of connections described, the back-lash in which train is taken up by the spring 97, swings slightly in counter-clockwise rotation with the shaft 106 and about the centre of said shaft until the point of the pawl 92 enters the path of the teeth 90 of the ratchet 90, when the oscillation of the pawl 92 by the eccentric 100 immediately produces a slight feeding upward of the label table, the ratchet being moved through a slight arc by the action of the pawl 92 and locked after each step of rotation by the pawl 91. During this operation the curler bar is swinging upwardly and through the mechanism connecting the shield and curler, swinging the shield 105 with the shaft 106 in 95 righthanded or clockwise rotation. After a very slight feeding operation, this motion of the shield moves the pawl 92 out of the path of the teeth of the ratchet 90, and feeding is discontinued until the level of the top label in the pack on which the curler bar rests, is again lowered to a point corresponding to the initial feeding position just described, when the feeding operation is repeated. 100

When it is desired to replenish the label supply on the table, the shield is swung in righthanded rotation by means of the handle 141, see Figure 5, or it may be otherwise engaged, the swing being sufficient under these circumstances to bring the hook 109 on the end of the shield into engagement with the 115 tail 110 of the locking pawl 91.

To prevent feeding of the table while it is lowered for the purpose of replenishing the labels, I have shown a dog 142 secured to the rod 86 at a point normally above the ratchet and capable of being secured to the rod at various points of adjustment by means of a set-screw 143, the dog 142 having an engaging point 144 to co-operate with a trigger arm 145 on the shaft 106 and serving to hold 120 125 130

the pawl shield in disengaging position as to the pawl 92, when the table is depressed, preventing feeding motion of the table during the replenishing operation.

5 I have also shown, particularly in Figure 5, an alarm intended to warn the operator just before the table reaches its uppermost position when the labels are nearly exhausted, calling attention to the condition of 10 the mechanism. This alarm consists of a dog 150 shown as secured to the end of the rack 87 by means of a collar 151 and set-screw 152, and being shown as L-shaped, as is the dog 142 previously described, and having 15 an actuating member 158 extending upwardly, and also to the right, see Figure 6, and adapted to engage the trigger point 153 of a helical spring arm 154 secured to the frame, as by means of a cap-screw 155 to 20 project outwardly therefrom and carrying a clapper 156 above and in close proximity to a gong 157. When the feeding has progressed to such an extent that the actuating member 158 of the dog engages the trigger 25 passes the actuating member 158 and releases it, the clapper snaps backward and raps the gong, producing the desired signal.

In Figure 23 I have shown a belt presser 159, the same being mounted in brackets 30 160, one on each side of the machine, and moving with the carriage 34. The bracket or follower 160 slides in a slot 161 in the label guide 162 to be described, the said follower being substantially of H-shaped cross-section, as shown in Figure 23', and being formed of a plate 163 having a projecting lug 164 to engage the slot 161, and a plate 165 secured thereto on the inside of the label 35 guide to hold the carrier in position, the parts being connected by screw 166 or in any suitable manner. The member 160 is moved back and forth with the paste belt and other parts on the carrier 31 by means of the shaft 135 which is passed through a vertical U-shaped slot 167 in the member 160. The belt presser extends across the label pack from side to side and is pivoted to each said follower 160 by means of studs 168 or in any suitable manner, the presser extending from 40 the pivots 168 backwardly, i. e., in the direction of feed and resting on the belt 29. The belt presser is provided with a U-shaped slot 171 between the belt engaging portion 170 extending upwardly from the bottom 45 where it is open to take over and avoid the curler 133. The paste belt 29 is normally spaced above the labels, avoiding accumulation of paste thereon, and is pressed down on the labels by each can as it passes, causing 50 the belt to engage the label just before the label is picked up. The pressing down of the belt is accomplished by the action of the can in passing, the belt presser being provided with a bump or protuberance 173 55 on its upper surface for this purpose, caus-

ing a considerable portion of the momentum of the can to be converted into a downward force, which actuates the belt presser as just described.

In Figures 11, 12, 13, 14, 15 and 16 I have 70 illustrated three different forms of label curler.

As previously known to the art, label curlers have been made with a single gripping edge extending across the label pack 75 from side to side, but some difficulty has been encountered due to the early failure of this edge due to wear. I have increased the life of the curler bar by providing from four to eight gripping edges. The first or regular 80 form of curler bar in my machine is square having four gripping edges 176 which are slotted transversely at 175, Figure 11, the width of the slots 175 determining the 85 amount of paste left on the lap ends of the labels. In the operation of this device there is a thin coating of paste, the bulk of the paste being scraped off by the edges 176 and at intervals a thicker coating in the form of strips of the width of the grooves 175 and of 90 a length corresponding to the width of the paste belt which is found to be a much more favorable distribution of the paste than any heretofore accomplished.

To further increase the life of the label 95 bar, I have devised the forms shown in cross-section in Figures 14 and 16, and in plan in Figures 13 and 15, respectively. The improvement consists in providing in the type shown in Figure 14, six label contacting 100 edges 178, and in the form shown in Figure 16, eight contacting edges 179 instead of the four contacting edges of the label curler bar, Figure 12. This is accomplished by turning a plurality of grooves in the face of a 105 cylindrical member or piece of shafting of the desired diameter of the curler bar. In Figure 14 there are three such grooves 180, and in Figure 16 the curler bar is formed 110 by cutting four such grooves 181 in the face of such a cylindrical bar or shaft, the grooves being equally spaced about the centre and spaced apart at the periphery by a distance sufficient to give the required thickness of metal between the engaging edges 78 and 79. 115 It is obvious that in the use of such a curler bar, as shown in Figures 14 and 16, half of the edges turned in one direction, i. e., in the righthanded or lefthanded direction, will become worn much sooner than the other half, 120 and that after a considerable period of use the operation of the curler bar may be improved by reversing it, taking advantage of the unworn edges.

In Figures 8, 9, 10 I have illustrated the 125 cement or glue spotting pot 65 whereby the cans are spotted with paste prior to picking up the labels. This is also shown in a general way in plan in Figs. 2 and 4. The cement is normally solid or semi-solid, and becomes 130

liquid when heated. The pot as formerly used consists of a reservoir at one side of the machine, forming a receptacle in which the hard cement may be placed, and a roller basin beneath the runway which is fed from the reservoir. It has been found undesirable to have the shaft of the rollers submerged, as it tends to accumulate the cement, applying an excess of cement to the cans. It is also undesirable to have partially melted masses of cement admitted to the roller basin.

To avoid these and other difficulties and to improve the efficiency of the cement spotting mechanism, I have revised and reconstructed the same on the improved lines illustrated.

The paste pot 65, as aforesaid, consists of a reservoir 185 to receive the solid cement as it is placed in the machine, and a roller basin 186 into which the cement rollers 69 dip, picking up a supply of liquid cement with which the cans are spotted. To maintain the level of the liquid cement below the shaft, or to keep it from rising to and above the shaft 72, the reservoir 185, see Figures 8, 9 and 10, is made comparatively shallow with the top edges of its sides or walls 187 spaced below the shaft 72, so that whatever quantity of cement is placed in the reservoir 185, the level in the roller basin cannot be raised above the shaft, as the liquid cement will overflow the reservoir 185 before the level of the liquid reaches the shaft 72. The passage of unmelted cement from the reservoir 185 to the roller basin 186 is prevented by making the passage 188, which connects the two portions of the cement pot, in the form of a narrow slot 188, so that it has the effect of a strainer, checking the tendency of solid unmelted portions of cement and debris to pass from the reservoir to the roller basin.

The rollers 69 have been described as mounted on the shaft 72, which is in turn driven by a belt 70 from the shaft 71', the connection between the shaft 72 carrying the rollers 69 and the pulley 71 being as shown in the form of toothed gears 188 connecting the shaft 72, carrying the rollers and the shaft 71' on which the pulley 71 is mounted.

The cement pot, as shown in Figures 9 and 10, is provided with an extension 190 in the direction of the feed, the same having an inclined bottom wall providing for the return to the roller basin of any excess cement which may be carried over and dropped by the can. The cement pot is heated by means of burners 192 beneath the roller basin or in any suitable manner.

I have also shown in Figures 2, 8 and 9 a drain cock 250 leading from the bottom of the cement pot 65 and provided with a plug valve 251 by which the paste may be drained from the bottom of the pot when desired. In accordance with the previous practice, the

paste-pot has been so arranged that it can be taken out and dumped from time to time.

In Figures 3 and 4 I have shown side guides 194 on the far side of the machine made in short sections and placed end to end. These are mounted on studs 195 at each end of each can guide, the studs being mounted to slide through the can guide bar 196, the can guides being controlled by helical springs 197 surrounding each stud and seated in sockets 198 in the bar, each spring bearing on the bottom of its socket and against the rod. The can guide 199 on the near side of the machine is in the form of a single rod extending from one to the other end of the traverse of the cans mounted on studs 200 at each end, the studs 200 being threaded and passed through upright lugs 201 on the brackets 9 and 10, being adjustable by means of thumb screws 202 and controlled by means of springs 203 coiled about the studs, bearing at one end against the lugs 201 and at the other against collars 204 pinned on the studs. The desirability of yielding guides to prevent cramping the cans and means for adjusting the guides in proper alignment are well understood.

Referring now to Figures 18, 19, 20 and 24, illustrating the label guides and the adjusting means therefor, it not infrequently happens that the entire pack of labels is cut or printed irregularly, i. e., with the printing out of alignment with the side edges, and in some instances the edges of the labels are not parallel. The canners adhere to varying standards as to the manner of applying the labels, some require that the label be set with the edges parallel to the edges of the can, and frequently it is required that the printing or picture on the label shall be square with the edges of the can, without regard to the position of the edges of the label. The present device provides an adjustment or a combination of adjustments of the label guides, whereby regularly or irregularly cut labels which are, however, all substantially uniform in each particular pack, may be applied with either edge parallel to the edges of the can, or in case the edges are out of alignment with the printing or the pictures, the labels may be applied with the printing and pictures square with the edges of the can.

Not only have I made the guides adjustable relatively to the machine frame toward and from each other, but I have so arranged the adjusting means that the two guides may be adjusted at each end toward or from each other equally and simultaneously, and either end of either guide may be moved transversely of the machine independently of the other guide.

Referring again to the drawings, the label guides are indicated by reference characters 162, 162', the guide 162 being on the lefthand

side of the machine facing in the direction of the feed and the guide 162' on the right-hand side of the machine, it being understood that the plan, Figure 18, is reversed in respect to the plans 3 and 4.

- The guides 162 and 162' are mounted on and secured to supports 206 and 207 on the opposite sides of the machine 206 on the left and 207 on the right in the direction of feed, 10 and these supports 206 and 207 are enlarged at each end forming lugs 208, Figure 24, which are in turn apertured, forming cylindrical downwardly disposed sockets 209, which are apertured to receive and enclose 15 cylindrical nuts 210, which as shown are apertured and threaded transversely at 211 to engage the adjusting screws to be described, and are further slotted vertically at 212 intersecting the apertures 211 to provide 20 an easy engagement of the screws by the nuts, and the lugs 208 are provided with enlarged apertures 213 to pass the adjusting screws and to permit of a slight vertical adjustment of the label guides by means of 25 vertical adjusting screws 214 seated in the lugs at the top and extending downward into the cavity or socket 209, and controlled to prevent loss of adjustment by means of 30 spring cupped washers 213.
- The label guide adjusting screws already referred to are shown in plan in Figure 18. They are four in number, one for each end of each guide and extend transversely of the can feed. While there are four adjusting 35 screws, they are placed in alignment two and two as hereinafter described, and each pair of aligned screws may be locked together to turn together to adjust the guides simultaneously and oppositely. When so locked 40 together each pair of aligned screws forms in effect a single screw or screw-shaft.
- Referring to the parts as right and left-hand, determined by an observer facing in the direction of feed, the righthand adjusting screws 218, one at each end of the right-hand guide 162', are hollowed out in the direction of its axis and provided each with a knurled head 219 by which it may be conveniently rotated by hand. This head or a 45 suitable shoulder 220 below the head bears against the side frame 2, the body of the screw extending through a suitable aperture 221 in the frame and being positioned by a pair of lock nuts 220 on the inside of 50 the frame member 2 which are held in position of adjustment by forcing one nut against the other, leaving the contact with the frame free so the screw turns freely in the frame. The adjusting screws 218 engage the nuts 210 carried by the righthand label guide 116 or the support 107 thereof, 55 one at each end of the support, the adjusting screws, etc., being duplicated at the two ends of the guides 162 and 162'. The left-hand label guide 162 is operated by the left- 60 hand or inside adjusting screws 225 which extend through the frame 1 and have heads 226 bearing on the outside of the frame member 1, being positioned by lock nuts 227 on the screws bearing against the cupped 65 spring washers 228 which in turn bear against the inside of the frame. The adjusting screws 225 turn freely in the frame and each has an enlarged threaded portion 229 which engages the nut 210 in the aperture 70 209 in the lug 208 in the end of the support 206 of the lefthand guide 162. The threaded portion 229 is discontinued near the centre of the space between the frames 1, 2 and beyond said threaded portion, the 75 screw-member is continued in the form of a small shaft or pin 230 which extends toward the observer or to the right in the direction of the feed through the hollow or axial opening in the screw 218 extending entirely 80 through the screw and beyond the knurled head 219, the portion of the shaft or rod 230 which projects from the head 219 of the screw 218 being slotted and provided with a second knurled head 231 which is 85 connected to the shaft 230 by a pin 232 which is seated in the knurled head 231 and enters the slot 230, and the knurled head 231 is provided with a pin or key 233 projecting therefrom toward the knurled head 219, and the latter is provided with a series of holes 234 on the face toward the head 231 to receive the pin 233 to lock the knurled head 219 and 231 together, locking the two screws 90 together to rotate simultaneously at the will 100 of the operator.
- On examination of the drawing it will be noted that the screws 218 and 229 are similarly threaded, so that when the screws 218, 225 are locked together by sliding the 105 knurled head 231 along the shaft 230 and pressing it against the knurled head 219, causing the pin 233 to enter one of the holes 234, and caused to rotate simultaneously in one direction or the other, the label guides 110 162 and 162' are moved as to the end of the guides engaged by the particular screw in question laterally of the machine without changing their relation to each other whether they are parallel or slightly at an angle. 115 The desired spacing of the guides is obtained by turning either screw separately to move either end of either guide.
- To move either end of either guide independently of the other guide, the knurled head 231 which slides on the shaft 230 is drawn back to the position shown in Figure 18, removing the pin 233 from the socket 234 in which it is seated, and disconnecting the screws, so that they are free to rotate 120 relatively to each other. Then the lefthand guide 162 or the particular end thereof engaged by either of the screws, may be moved back and forth transversely of the machine by rotating the thumb nuts or hand-wheels 125 130

231, and the righthand guide 162' or the end thereof adjacent either of the screws can be moved back and forth transversely of the frame by rotating either hand-wheel 5 or thumb nut 219.

It is thus apparent that the alignment or position of the guides or either of them can be conveniently changed at will by means of the same mechanism with but a slight 10 shift of the arrangement thereof, and that when the desired relation of the guides is attained, they may be adjusted simultaneously to give any desired angle to the labels.

By reference to Figures 18 and 23 it will 15 be noted that the top edges of the guides 162, 162' form a way for the cans on which they roll over the label pack, picking up the top label by means of a spot of cement previously placed on the can. It will also be 20 noted that the guide is slotted at 161 to provide for the motion of the lap end pasting belt 29, curler shaft 135, curler 133, belt presser 159, etc., which move with the paste pot.

25 The operation of the various mechanisms disclosed have been fully described in connection with the description of the parts and details of the machine.

I have thus described specifically and in 30 detail a single embodiment of the machine of my invention in order that the nature and operation of the same may be clearly understood; however, the specific terms herein are used descriptively rather than in 35 a limiting sense, the scope of the invention being defined in the claims.

What I claim and desire to secure by Letters Patent is:

1. In a can labeling machine having a feed 40 belt engaging the cans from above to roll them through the machine, and feed belt pulleys at opposite ends of the machine, means for equally and simultaneously adjusting the feed belt and the feed belt pulleys at the opposite ends of the machine up or down to provide for treating cans of different diameters.

2. In a can labeling machine, ways, a feed 50 belt for moving the cans along the ways, pulleys for said belt at the opposite ends of the machine, a support for each said pulley mounted to move up and down, separate means for moving each of said supports up and down, and means connecting said means 55 for moving the supports at the opposite ends of the machine together whereby the pulleys at the opposite ends of the machine may be adjusted up and down equally and simultaneously by a single operation.

60 3. In a can labeling machine, means for feeding cans through the machine, comprising a feed belt, pulleys at each end of the machine carrying said belt, means supporting said pulleys adapted to move up and down, means for actuating each of said sup-

ports to move up and down, and means connecting said actuating means at the opposite end of the machine together whereby the pulleys and supports and belt are moved up and down simultaneously, can spotting mechanism mounted to move longitudinally of the machine, lap end pasting mechanism, and means supporting the same, so that it may be moved longitudinally of the machine, and actuating means connecting said can spotting mechanism, and said lap end pasting mechanism, respectively, to said actuating mechanism at the opposite ends of the machine and co-operating therewith, whereby the spotting mechanism and the lap end pasting mechanism are moved along the machine as the feed belt and pulleys are moved up and down.

4. In a can labeling machine a support 85 for the cans and a feed belt for moving the cans longitudinally of the machine, a pulley for the belt at each end of the machine, means supporting the pulleys, said supports being mounted for vertical adjustment, a motor for driving one of said belt pulleys, 90 and means for connecting the motor to the pulley, including a telescoping shaft having means for preventing relative rotating motion of the telescoping parts.

5. In a can labeling machine, a support 95 for the cans and a feed belt for moving the cans longitudinally of the machine, a pulley for the belt at each end of the machine, means supporting the pulleys, said supports being mounted for vertical adjustment, a 100 motor for driving one of said belt pulleys, and means for connecting the motor to the pulley, including a telescoping shaft having means for preventing relative rotating motion of the telescoping parts, and a flexible 105 joint at each end of the telescoping shaft.

6. In a can labeling machine, a support for the cans and a feed belt for moving the cans longitudinally of the machine, a pulley 110 for the belt at each end of the machine, means supporting the pulleys, said supports being mounted for vertical adjustment, a motor for driving one of said belt pulleys, and means for connecting the motor to the pulley including a telescoping shaft having 115 the telescoping members square, preventing relative rotating motion of the telescoping parts, and a flexible joint in said shaft.

7. In a can labeling machine, a support for the cans and a belt for moving the cans along the support, a pulley for the belt at each end of the machine, a support for each pulley mounted to move vertically, can spotting mechanism mounted to move longitudinally 120 of the machine, means for driving the can feed belt, a pulley for driving the can spotting mechanism with a belt driving said pulley and connected to the can feed pulley at each end of the machine to be driven therefrom, means for tightening said belt driving 125 130

- the can spotting mechanism consisting of two pulleys engaging the two stretches of said belt from the same side, and means pressing said pulleys against the belt to maintain the tension thereof as the adjustment of the belt feed pulley and the can spotting mechanism is changed.
8. In a can labeling machine, a support for the cans and a belt for moving the cans along the support, a pulley for the belt at each end of the machine, a support for each pulley mounted to move vertically, can spotting mechanism mounted to move longitudinally of the machine, means for driving the can feed belt, a pulley for driving the can spotting mechanism, a belt driving said pulley and connected to the can feed pulley at each end of the machine to be driven therefrom, means for tightening said belt driving the can spotting mechanism consisting of an arm, two pulleys mounted thereon engaging the two stretches of said belt from the same side, and means pressing said pulleys against the belt to maintain the tension thereof as the adjustment of the belt feed pulley and the can spotting mechanism is changed, means for moving the feed belt pulley supports at each end of the machine up and down, and means connecting said means together to move said supports simultaneously, adjusting the feed belt up and down, and means connecting the can spotting mechanism to said belt, adjusting means to be actuated thereby, moving the can spotting mechanism along the ways as the feed belt moves up and down.
9. In a can labeling machine having a feed belt engaging the cans from above and rolling them through the machine, and means for moving said belt up and down, means for spotting the cans with cement as they pass, and means supporting the same on the machine, permitting the same to be moved in the direction of feed, and means connecting said paste spotting mechanism to the feed belt adjusting means providing for longitudinal motion of the spotting mechanism as the feed belt is moved up and down.
10. In a can labeling machine having a feed belt engaging the cans from above and rolling them through the machine, feed belt pulleys at each end of the machine carrying said feed belt, a support for each said pulley, and means for guiding each said support in a vertical direction, and means for moving each said support up and down, means for spotting the cans with cement as they pass, and means supporting the same on the machine, permitting the same to be moved in the direction of feed, and means connecting said paste spotting mechanism to the feed belt pulley moving means providing for longitudinal motion of the spotting mechanism as the belt pulleys are moved up and down, and additional means for adjust-
- ing said paste spotting mechanism longitudinally of the machine and relatively to and independently of said first-mentioned means for adjusting the same.
11. In a can labeling machine, a can feed belt engaging the cans from above, and rolling them through the machine, a pulley for said belt at each end of the machine, and means for supporting said pulleys, means for guiding the supports vertically, means for moving the support at one end of the machine up and down, adjusting the position of the belt, can spotting mechanism including a glue pot with rollers beneath the path of the cans, and a pulley for rotating the rollers, guides for the same in a longitudinal direction, and means connecting the can spotting mechanism to the feed belt pulley to the means for moving the feed belt pulley mechanism, causing said parts to move longitudinally of the machine as the feed belt pulley is moved up and down.
12. In a can labeling machine, a can feed belt engaging the cans from above and rolling them through the machine, a pulley for said belt, means for moving the belt and pulley up and down, adjusting the position of the belt, can spotting mechanism including a glue pot with rollers beneath the path of the cans, and a pulley for rotating the rollers, guides and supports for the same permitting them to be moved in a longitudinal direction, and means connecting the can spotting mechanism to the means for moving the feed belt, causing said parts to move longitudinally of the machine as the feed belt is moved up and down, a pulley connected to the feed belt pulley to rotate therewith, a belt connecting the same to the pulley on the can spotting mechanism, and means for applying a yielding tension to said belt to keep it tight when the parts including all feed pulleys are moved to various positions of adjustment.
13. In a can labeling machine, means for feeding cans through the machine, comprising a feed belt, means for moving said belt up and down providing for a variation in the diameters of the cans, label feeding means and lap end pasting mechanism including a paste belt and a pulley, a shaft for said pulley extending longitudinally of the machine, and means for connecting said latter pulley to the means for moving the feed belt whereby the lap end pasting belt and said latter pulley are moved longitudinally of the machine as the feed pulley is moved up and down.
14. In a can labeling machine, a feed belt engaging the cans from above and rolling them through the machine, means for moving the belt up and down, comprising a vertical rack and a pinion, a label support and lap pasting mechanism, the latter being mounted to move longitudinally of the ma-

chine, a rack connected to the lap pasting mechanism and extending longitudinally of the machine, and a pinion engaging said longitudinal rack and connected to the first-mentioned pinion.

15. In a can labeling machine, a feed belt engaging the cans from above and rolling them through the machine, means for moving the belt up and down, comprising a vertical rack and a pinion, a label support and lap pasting mechanism, the latter being mounted to move longitudinally of the machine, a rack connected to the lap pasting mechanism and extending longitudinally of the machine, a pinion engaging said longitudinal rack and connected to the first-mentioned pinion, and means for adjusting the longitudinal rack relatively to the lap pasting mechanism.

20. 16. In a can labeling machine, a feed belt engaging the cans from above and rolling them through the machine, means for adjusting the feed belt up and down comprising a rack and pinion, can spotting mechanism mounted to move longitudinally of the machine, a longitudinally extending rack connected to said can spotting mechanism, a pinion engaging said rack and connected to the first-mentioned pinion to rotate therewith, moving the can spotting mechanism longitudinally of the machine as the belt is adjusted up and down.

17. In a can labeling machine, a feed belt engaging the cans from above and rolling them through the machine, means for adjusting the feed belt up and down comprising a rack and pinion, can spotting mechanism mounted to move longitudinally of the machine, a longitudinally extending rack connected to said can spotting mechanism, a pinion engaging said rack and connected to the first-mentioned pinion to rotate therewith, moving the can spotting mechanism longitudinally of the machine as the belt is adjusted up and down, and means for adjusting the can spotting mechanism relatively to the longitudinal rack.

18. In a can labeling machine, a feed belt engaging the cans from above and rolling them through the machine, a pulley for said belt at each end of the machine, and means for adjusting the pulleys up and down, comprising a vertical rack connected to each said pulley, a vertical guide and a pinion for each said rack, each pinion meshing with the corresponding rack, can spotting mechanism and lap end pasting mechanism mounted to move along the machine, a longitudinal rack connected to each said mechanism, a pinion connected to each said aforementioned pinion, each meshing with one said longitudinal rack, means for rotating the pinions engaging the vertical rack to move the feed belt up and down and to move the lap end pasting mechanism and the can spotting mecha-

nism simultaneously longitudinally of the machine to provide for the variation in the diameter of cans.

19. In a can labeling machine, a feed belt engaging the cans from above and rolling them through the machine, a pulley for said belt at each end of the machine, and means for adjusting the pulleys up and down, comprising a vertical rack connected to each said pulley, a vertical guide and a pinion for each said rack, each pinion meshing with the corresponding rack, can spotting mechanism and lap end pasting mechanism mounted to move along the machine, a longitudinal rack connected to each said mechanism, a pinion connected to each said aforementioned pinion and meshing with one said longitudinal rack, and means connecting the pinions at the opposite ends of the machine together whereby they may be rotated simultaneously to move the feed belt pulleys up or down equally and simultaneously at the same time moving the can spotting mechanism and the lap end pasting mechanism corresponding distances longitudinally of the machine, providing for variation in diameter of the cans and of the length of the labels.

20. In a can labeling machine, a feed belt engaging the cans from above to roll through the machine, means for moving the feed belt up and down, lap end pasting mechanism, means connecting the lap end pasting mechanism to the mechanism for moving the feed belt, causing the lap pasting mechanism to move longitudinally as the feed belt moves up and down.

21. In a can labeling machine, a feed belt engaging the cans from above to roll them through the machine, means for moving the feed belt up and down to compensate for the variation of the diameter of the cans, lap end pasting mechanism including a transversely extending paste belt, and pulleys, a pad and a way for the cans, the pulleys pad and way being mounted to slide longitudinally to the machine and means connecting them to the feed belt moving mechanism causing them to move longitudinally of the machine as the feed belt moves up and down.

22. In a can labeling machine, having a label table, ways above the table and, means for passing the cans along the ways, means for feeding the table to present the labels to the cans, and for controlling the feed and maintaining the top of the label pack at the height of the ways, comprising a ratchet, means for preventing backward rotation of the ratchet, a pawl, means for continuously oscillating the pawl, and means controlling said pawl, permitting the same to engage the ratchet intermittently and rotate the same at intervals, comprising a member resting on the top label of the pack, the vertical po-

- sition of said member being determined by the height of the label pack, and means connecting the latter to the pawl to control the same, permitting it to operate only when the top label is below a certain predetermined point.
23. In a can labeling machine, having ways, and means for feeding cans along the ways, a label table, means for feeding the table toward the ways to present the labels to the cans so that the top label may be taken up by each can in passing, and means for controlling said feeding means, a movable member resting on the top label of the pack and conforming to the vertical position of the top label, and means communicating the motion of said member to the controlling means, permitting the feed to operate when the top label is below a certain point.
24. In a can labeling machine, having ways, and means for feeding cans along the ways, a label table, and means for feeding the label table toward the ways, including a ratchet, a pawl engaging the ratchet to prevent backward rotation, a feed pawl cooperating with the ratchet to rotate the same and feed the table, means for continually oscillating the feed pawl, a spring tending to maintain it in engagement with the ratchet, a shield normally holding the pawl out of engagement with the ratchet, a member resting on the top label of the pack and conforming to the position of the top label, and means for communicating the motion of said member to the shield to control the periods of engagement of the pawl with the ratchet, and hence the operation of the latter.
25. In a can labeling machine, having means for supporting the cans and feeding them through the machine, a label table adjacent the can supporting means, means for feeding the table toward the path of the cans, and means for spotting the cans with paste so that each can passes over the label pack, taking up the top label, said table feeding means including a ratchet, means for preventing backward rotation of the ratchet, a pawl adapted to engage the ratchet and feed the same, means for oscillating the pawl, means tending to maintain the pawl in engagement with the ratchet, a shield holding the pawl out of engagement with the ratchet, a label curler resting on the top label of the pack and conforming to the position of the top label, means for communicating the motion of the label curler to the shield to control the position of the feeding pawl, permitting the pawl to engage the ratchet when the curler drops below a certain point and releasing the pawl, throwing it out of engagement when the label pack is raised to contact the cans.
26. In a can labeling machine, having a can support and means for feeding cans along the support, a label table, means for feeding the table toward the support, comprising a rack and pinion, a ratchet gear connected to the pinion to rotate the same, means for locking the ratchet gear against backward rotation, a feeding pawl normally in engagement with the ratchet, a member resting on top of the label pack and moving in accordance with the variation in height of the top label of the pack, a shield engaging the feeding pawl and connection from said shield to said member resting on the label pack whereby the shield and pawl are controlled by said member, the shield being moved to release the pawl only when the top of the pack is below a certain point, and means for oscillating the pawl.
27. In a can labeling machine, having means for feeding and supporting cans, a label table, means tending to feed the table continuously toward the path of the cans, means for controlling said feed, holding it normally in inoperative position, and means for actuating said control, permitting the feeding means to operate at intervals as the top of the pack drops below a predetermined level, comprising a member resting on the top of the label pack and conforming to the position of the top label of the pack, and means connecting the same to the control to move the same in response to the motion of said member.
28. In a can labeling machine having ways for the cans, a label table, means for feeding the table toward the ways, tending to bring the top label of the pack into contact with each can as it passes, including a ratchet, means for locking the ratchet against backward rotation, a feeding pawl movably mounted, means operated by the power of the machine to oscillate the feeding pawl to rotate the ratchet, a shield engaging the pawl from the side toward the ratchet, a member resting on the top label of the pack, and means supporting the same, permitting it to conform to the position of the top label of the pack, connections from said member to the shield controlling the shield, a spring pressing on the pawl tending to maintain it in engagement with the ratchet, and likewise pressing it against the shield, the spring also serving to take up the back-lash in said connections, and to press the said member against the top label of the pack.
29. In a can labeling machine, having ways for the cans and means for moving the cans along the ways, a label table, means for feeding the table toward the ways, comprising a ratchet and a feed pawl, a locking pawl to prevent backward rotation of the ratchet, a shield normally engaging the feed pawl and normally spaced away from the

locking pawl, means for oscillating the feed pawl from the driven portions of the machine, a member engaging the top label of the pack, and means supporting the same to move in accordance with the variation in position of the top label, and means connecting the said member to the shield to control the latter and release the feed pawl, causing it to engage the ratchet when the top label drops below a predetermined point.

30. In a can labeling machine having ways for the cans and means for moving the cans along the ways, a label table, means for feeding the table toward the ways, comprising a ratchet and a feed pawl, a locking pawl to prevent backward rotation of the ratchet, a shield normally engaging the feed pawl and normally spaced away from the locking pawl, means for oscillating the feed

20 pawl from the driven portions of the machine, a member engaging the top label of the pack, and means supporting the same to move in accordance with the variation in position of the top label, and means connecting the said member to the shield to control the latter and release the feed pawl, causing it to engage the ratchet when the top label drops below a predetermined point, and a spring actuating the feed pawl tending to

25 maintain it in engagement with the ratchet, taking up the back-lash in connection with the said member and pressing the latter against the label pack, and means for adjusting the connection between the pawl and 30 the label pressing member to produce the relation of the parts described.

31. In a can labeling machine having means for feeding cans, a label table, means for feeding the same toward the path of the cans to bring the top label into the path of the cans, said means comprising a ratchet, a pawl, a shield beneath the pawl tending to keep it out of engagement with the ratchet, means driven by the machine oscillating the pawl to feed the ratchet, a member resting on the label pack and means supporting the same, permitting it to conform to the position of the top label, means connecting said member to the shield, comprising a rotatable shaft, and means connecting said member to said shaft, causing the shaft to oscillate in response to the variation of the height of the label pack.

32. In a can labeling machine having means for feeding cans, a label table, means for feeding the same toward the path of the cans to bring the top label into the path of the cans, said means comprising a ratchet, a pawl, a shield beneath the pawl tending to keep it out of engagement with the ratchet, means driven by the machine oscillating the pawl to feed the ratchet, a member resting on the label pack and means supporting the same, permitting it to con-

form to the position of the top label, means connecting said member to the shield, comprising a rotatable shaft, means connecting said member to said shaft, causing the shaft to oscillate in response to the variation of the height of the label pack, and a spring pressing on the pawl and taking up the back-lash of said connections.

33. In a can labeling machine, a can support, means for feeding cans along the support, a label table, means for feeding the label table toward the support, comprising a ratchet, a locking pawl, an oscillating feed pawl, means for manually throwing both said pawls out of engagement to provide for lowering the table and means connected to the table and engaging said throw-out means to maintain the pawls in inoperative position to prevent feeding of the table when it is thus lowered.

34. In a can labeling machine, a belt for feeding cans through the machine, means for adjusting the belt up and down to provide for variation in diameter of the cans, lap end pasting mechanism, means for moving the same longitudinally of the machine, the same being connected to said belt moving means, the lap end pasting mechanism comprising a paste belt and a paste pot, a belt presser, and a label curler, and means connecting all of said members including the belt presser, the label curler being connected to the lap end pasting mechanism to move therewith.

35. In a can labeling machine, means for supporting cans, a feed belt for moving the cans through the machine, means for adjusting the belt up and down, lap end pasting mechanism, means connecting the same to the belt moving means to move the lap end pasting mechanism longitudinally of the machine as the belt moves up and down, a label curler pivotally mounted on said lap end pasting mechanism, a lap pasting belt, a belt presser for engaging the same, and means supporting said presser mounted to slide longitudinally of the machine and engaging said label curler whereby it is moved with the label curler.

36. In a can labeling machine, having ways for the cans, a can spotting mechanism comprising a roller basin for melted cement beneath the path of the cans with rollers therein and a roller shaft with means for rotating the same, and a reservoir with means for heating the cement connected to said basin, the reservoir having the top edges of its side walls below the level of the roller shaft.

37. In a can labeling machine, a can spotting mechanism comprising a roller basin for melted cement beneath the path of the cans with rollers therein and a roller shaft with means for rotating the same, a reser-

voir with means for heating the cement connected to said basin, the reservoir having an aperture for releasing liquid cement above the bottom of the basin and below the level 5 of the shaft.

38. In a can labeling machine, can spotting mechanism comprising cement spotting rollers, means for rotating the same, a roller basin containing the rollers and adapted to 10 contain liquid cement, means for rotating the rollers, a reservoir for a reserve supply of cement, and a passage in the form of a narrow horizontal slot connecting the reservoir and the basin to provide for the passage 15 of liquid cement and to prevent the passage of solid portions of cement and the like.

39. In a can labeling machine, can spotting mechanism comprising cement spotting rollers, means for rotating the same, a roller 20 basin containing the rollers and adapted to contain liquid cement, means for rotating the rollers, a reservoir for cement, and a passage in the form of a narrow slot connecting the reservoir and the basin to provide 25 for the passage of liquid cement and to prevent the passage of solid portions of cement and the like.

40. In a can labeling machine, a label curler for curling the lap ends of the labels 30 as they are taken up from the pack, comprising a transverse rod having longitudinal ribs on its surface with two label engaging edges on each rib one on each side.

41. In a can labeling machine, a label 35 curler for curling the lap ends of the labels as they are taken up from the pack, comprising a transverse rod having longitudinal ribs on its surface with two label engaging edges on each rib, one on each side, the said 40 ribs being slotted at intervals transversely to the length of the bar.

42. In a can labeling machine, means for 45 feeding cans, a label table, label guides on each side of the table acting as ways for the cans, lap pasting mechanism and a label curler, and a belt presser connected to the lap pasting mechanism, and means for adjusting all these mechanisms longitudinally 50 of the machine, the guides being slotted to permit the motion of the label curler and the belt presser.

43. In a can labeling machine, means for 55 feeding cans through the machine, a label table and label guides beneath the path of the cans and spaced apart and extending in the direction of feed to guide the labels as they are presented to the cans, and means for adjusting the guides transversely of the feed comprising two transverse threaded 60 members at each end of the guides and a nut at each end of each guide, each nut engaging one of said screw-threaded members, and means for manually engaging each said screw-threaded members for moving each

end of each guide separately in either direction transversely of the machine, and means for connecting the two threaded members at each respective end of the machine together so that the two adjacent ends of the two guides may be moved simultaneously transversely of the machine without changing their relation to each other. 65

44. In a can labeling machine, means for feeding cans through the machine, a label table and label guides beneath the path of 70 the cans and spaced apart and extending in the direction of feed to guide the labels as they are presented to the cans, and means for adjusting the guides transversely of the feed comprising two transverse screw-shafts 75 at each end of the machine and a nut on each end of each guide engaging the corresponding screw-shaft, one said shaft on each end of the machine being hollow and the other said screw-shaft at each end of the machine extending through said hollow portion, means for locking the inside and outside 80 shafts together at the will of the operator, so that they may be rotated simultaneously. 85

45. In a can labeling machine, means for feeding cans through the machine, a label table and label guides beneath the path of 90 the cans and spaced apart and extending in the direction of feed to guide the labels as they are presented to the cans, and means for adjusting the guides transversely of the feed comprising two transverse screw-shafts 95 at each end of the machine and a nut on each end of each guide engaging the corresponding screw-shaft, one said shaft on each end 100 of the machine being hollow and the other said screw-shaft at each end of the machine extending through said hollow portion, means for locking the inside and outside shafts together at the will of the operator, 105 so that they may be rotated simultaneously, and means for manually engaging each said shaft for rotating the same. 110

46. In a can labeling machine, means for feeding cans through the machine, a label 110 table and label guides beneath the path of the cans and spaced apart and extending in the direction of feed to guide the labels as they are presented to the cans, and means for adjusting the guides transversely of the feed 115 comprising two transverse screw-shafts and a nut on an end of each guide engaging the corresponding screw-shaft, one said shaft being hollow and the other said screw-shaft extending through said hollow portion, means for locking the inside and outside 120 shafts together at the will of the operator, so that they may be rotated simultaneously, the threads on said inside and outside shafts being similar. 125

47. In a can labeling machine, means for feeding cans through the machine, a label table and label guides beneath the path of

- the cans and spaced apart and extending in the direction of feed to guide the labels as they are presented to the cans, and means for adjusting the guides transversely of the feed comprising two transverse screw-shafts, and a nut on each guide engaging the corresponding screw-shaft, one said shaft being hollow and the other said screw-shaft extending through said hollow portion, means for locking the inside and outside shafts together at the will of the operator, so that they may be rotated simultaneously, and means for manually engaging each said shaft for rotating the same, said manual engaging means comprising a member secured to the hollow shaft and a co-operating member secured to the inside shaft, the latter member being mounted on the inside shaft to slide relatively thereto and having means for engaging the member on the hollow shaft in a plurality of positions of angular adjustment.
48. In a can labeling machine, means for feeding cans through the machine, a label table and label guides beneath the path of the cans and spaced apart and extending in the direction of feed to guide the labels as they are presented to the cans, and means for separately adjusting an end of each guide transversely of the feed.
49. In a can labeling machine, means for feeding cans through the machine, label guides beneath the path of the cans and spaced apart and extending in the direction of feed to guide the labels as they are presented to the cans, and means for separately adjusting the ends of the guides transversely to the feed and means for adjusting the adjacent ends of the guides simultaneously without changing their relation.
50. In a can labeling machine, means for feeding cans through the machine and label guides spaced apart and extending in the direction of the feed to guide the labels as they are presented to the cans, and means for adjusting the ends of the guides transversely of the feed comprising two transverse threaded members and a nut on the end of each guide, each nut engaging one of said screw-threaded members, and means for manually engaging each of said screw-threaded members for moving an end of each corresponding guide separately in either direction transversely of the machine.
51. In a can labeling machine, means for feeding cans through the machine and label guides spaced apart and extending in the direction of the feed to guide the labels as they are presented to the cans, and means for adjusting the ends of the guides transversely of the feed comprising two transverse threaded members and a nut on the end of each guide, each nut engaging one of said screw-threaded members, means for manually engaging each of said screw-threaded members for moving an end of each corresponding guide separately in either direction transversely of the machine, and means for connecting the two threaded members together to rotate together.
52. In a can labeling machine, means for supporting a pack of labels, means for feeding the cans over the labels, and means for spotting the cans to enable them to pick up the labels, and a label curler consisting of a bar of square cross-section, and means for supporting the same so that it rests on the labels.
53. In a can labeling machine, means for supporting a pack of labels, means for feeding the cans over the labels, and means for spotting the cans to enable them to pick up the labels, and a label curler consisting of a bar of square cross-section, and means for supporting the same so that it rests on the labels with a corner depressed.
54. In a can labeling machine, means for supporting a pack of labels, means for feeding the cans over the labels, and means for spotting the cans to enable them to pick up the labels, and a label curler consisting of a bar of angular cross-section, and means for supporting the same so that it rests on the labels, the curler bar having grooves transverse to the edges of the bar having a plurality of longitudinally extending flat label engaging surfaces.
55. In a can labeling machine, means for supporting a pack of labels, means for feeding cans over the label pack, means for spotting the cans as they pass, comprising a cement pot, and means for heating the same, paste-applying means dipping in said pot, and means for draining the paste-pot comprising an outlet passage at the bottom of the paste-pot, and means for closing the same at the will of the operator.
56. In a can labeling machine, means for feeding cans through the machine, a label table and label guides on the table spaced apart to engage the opposite edges of the label, the table being beneath the path of the cans and the guides extending in the direction of the feed to guide the labels as they are presented to the cans, and means for separately moving an end of a guide transversely of the feed independently of the other end for purposes of adjustment.
57. In a can labeling machine, means for feeding cans through the machine, a label table and guides on the table spaced apart to engage the opposite edges of the label, the table being beneath the path of the cans and the guides extending in the direction of the feed to guide the labels as they are presented to the cans, and means for simultaneously adjusting adjacent ends of the two guides independently of the other ends.

58. In a can labeling machine, means for feeding cans through the machine, a label table and guides on the table spaced apart to engage the opposite edges of the label, the table being beneath the path of the cans and the guides extending in the direction of the feed to guide the labels as they are present- ed to the cans, and means for moving both guides to vary their direction in a horizontal plane and relatively to the direction of feed. ^w
